CLAIM

The ornamental design for an enclosure for sensors and transmitters for HVAC/R applications, as shown and described.

DESCRIPTION

FIG. 1 is a top, front and right side perspective view of an enclosure for sensors and transmitters for HVAC/R applications in accordance with my new design;

FIG. 2 is a top, front and left side perspective view of the enclosure shown in FIG. 1;

FIG. 3 is a front elevation view of the enclosure shown in FIG. 1;

FIG. 4 is a right side elevation view of the enclosure shown in FIG. 1;

FIG. 5 is a left side elevation view of the enclosure shown in FIG. 1;

FIG. 6 is a top plan view of the enclosure shown in FIG. 1;

FIG. 7 is a bottom plan view of the enclosure shown in FIG. 1;

FIG. 8 is a top, front and right side perspective view of a second enclosure for sensors and transmitters for HVAC/R applications in accordance with my new design;

FIG. 9 is a top, front and left side perspective view of the enclosure shown in FIG. 8;

FIG. 10 is a front elevation view of the enclosure shown in FIG. 8;

FIG. 11 is a right side elevation view of the enclosure shown in FIG. 8;

FIG. 12 is a left side elevation view of the enclosure shown in FIG. 8;

FIG. 13 is a top plan view of the enclosure shown in FIG. 8; and,

FIG. 14 is a bottom plan view of the enclosure shown in FIG. 8.

The rears of the enclosures do not comprise any portion of the invention, and hence are not shown in the drawings.

The broken line showings are for illustrative purposes only and form no part of the claimed design.

1 Claim, 12 Drawing Sheets
